UNITED STATES PATENT OFFICE

WILLIAM L. McNAMARA, OF CONNELLSVILLE, PENNSYLVANIA, ASSIGNOR TO CAPSTAN GLASS COMPANY, OF CONNELLSVILLE, PENNSYLVANIA, A CORPORATION OF DELAWARE

TRIPPING DEVICE

Application filed October 19, 1928. Serial No. 313,479.

The present invention relates to tripping devices for leers and is an improvement in part of the invention disclosed in my Application S. N. 297,661, filed August 6, 1928, Patent No. 1,842,912.

In transferring vessels to leers by means of loaders actuated by moving vessels, difficulty has been encountered due to vessels being deranged or broken when the loader moves inwardly toward the leer. The vessels in many cases are relatively tall in comparison with the size of their bases which makes them topple over if not moved smoothly. The vessels may be conveyed to a position in front of the loader by means of a continuously moving belt. With the present loaders of this type, the forward vessel engages the tripping device and presses against it under the influence of the moving belt and is in this position when the trip is actuated and the transferring mechanism moved forward to transfer the vessels into the leer. The forward vessel, in its movement toward the leer, must slide across the tripping member. In many instances, the forward vessel fails to engage the trip squarely and this increases the difficulty. The end of the pusher or transferring mechanism has to clear the movable trip which causes the vessel to be engaged substantially by the end of the pusher. Frequently, vessels are caught between the end of the pusher and the side of the leer and crushed. The glass from the broken vessel tends to impair both the operation of the leer and the loader. In some cases, the forward vessel engages the trip prior to the pusher being in position to start its cycle of movement, which is very objectionable.

The present invention eliminates these difficulties by avoiding the sliding movement between the vessel and the trip and by securely supporting the vessels at all times until they are deposited within the leer. In addition, the trip cannot be operated until the loader is in position to start its cycle of movement.

An object of the invention is to provide an inexpensive tripping device which is simple in operation and which will eliminate or

minimize derangement of the vessels occasioned by contact with the device.

Another object of the invention is to eliminate the breakage of vessels occasioned by the forward vessel being caught between the end of the transferring mechanism and the side of the leer. 55

Another object of the invention is to provide a tripping device which moves with the vessels to hold them in proper position. 60

Another object of the invention is to provide a tripping device which is movable with a mechanism for transferring the vessels into proper position and which slides on the means which it operates to initiate the movement of the mechanism. 65

Other and further objects of the invention will be apparent from an understanding of the illustrative embodiment about to be described, or will be indicated in the appended claims, and various advantages not referred to herein will occur to one skilled in the art upon employment of the invention in practice. 70

A preferred embodiment of the invention has been chosen for the purpose of illustration and description and is shown in the accompanying drawings, wherein 75

Figure 1 is a side elevational view of a leer loader at the end of a leer with a tripping device in accordance with the present invention attached thereto; 80

Figure 2 is an end elevational view of the mechanism shown in Figure 1;

Figure 3 is a vertical sectional view through the center of the tripping device showing it attached to the transferring mechanism; and 85

Figure 4 is a perspective view of the tripping device. 90

Referring more particularly to the drawings there is shown a leer 1 having the usual opening 2, for the reception of glass to be annealed. A conveyor belt 4 extends through the opening and through the leer for conveying the ware at the proper rate of speed for the annealing operation. In order to prevent drafts, the end of the leer is closed in by a box or framework 5. A conveyor 6, extending over pulleys 7, has its upper strand 95

extending through the box 5 and supported by the bottom thereof. The belt is directly adjacent the conveyor 4 in the leer and has a narrow apron 8 extending between the conveyor 6 and the leer conveyor 4 in order to give a smooth surface over which the vessels travel.

The vessels 9 travel on conveyors or otherwise, and eventually reach the conveyor 6 and form in a continuous line thereon as shown, across the end of the leer. It will be noted that these vessels are inclosed in the box 5 and that a pair of horizontal bars 10 secured together by vertical members 11 form a pusher 13 for pushing the vessels off the belt 6 over the apron 8 and onto the conveyor 4. The mechanism for operating the pusher is not shown herein but preferably the pusher is moved forward to push the row of vessels onto the leer conveyor, then upward to clear the incoming vessels on the belt 6, then rearward over the incoming vessels, and downwardly to its original position.

In order to secure maximum capacity from the annealing leer, it is desirable that the transferring mechanism operate only when a full line of vessels is present. It is, therefore, convenient to have the mechanism responsive to the line of vessels in order to initiate the movement at the proper time. To achieve this purpose, there is provided a lever 12 pivoted on the bracket 14 which may be rigidly attached to the leer. The movement of this lever is adapted to initiate each cycle of movement of the transferring mechanism. Naturally, this may be done in many ways, for example, by electrically operated means, the movement of the lever 12 closing a particular circuit. Preferably, the transferring mechanism is operated by means of an air valve 15 which, with the stem 16 pressed inwardly, admits air to the cylinders which will give to the pusher members the cycle of movements described above. A suitable mechanism for this purpose may be found in my prior application, S. N. 297,661.

Mounted on the end of the pusher members 10 is a tripping device 17 comprising an L-shaped casting 18. The shorter leg of the casting, is attached by means of suitable bolts 19 to the members 10; the longer part of the casting extends transversely over the belt 6 in position to be engaged by the forward vessel moving thereon irrespective of the size thereof. On the back of the member 18 are a pair of extensions 20 adapted to receive a pin 21 held in position by screws 22. The small pin 21 extends through the bearing 24 to pivot the downwardly depending member 25. The latter has attached to its lower end by means of the bolts 27, a vessel engaging extension 26. The extension 26 is mounted below the lower edge of the member 17 and extends a substantial distance inwardly beyond the member 17, as will be

noted in Figure 3. The outward movement of the member 25, when engaged by a vessel on the conveyor 6, is determined by the yoke 28 formed by the cross-member 29 bolted to the extensions 30 on the L-shaped member 18. Secured to the back of the pivoted member 25 is a horizontal portion 32 which is adapted to engage the lever 12.

In the operation of the device, the vessels 9 are conveyed to the conveyor 6 in any suitable manner and are carried by it to a position in front of the pusher bars 10, as shown in Fig. 1. The distance between the respective vessels on the conveyor may be determined by mechanisms such as disks intermediate the conveyors rotated at the desired speed. As the row of vessels continues to move forward, the forward vessel 35 engages the lower end 26 of the pivoted member 25, which moves outwardly as shown in Figure 3 so that its laterally extending part 32 engages and moves the lever 12. As explained, the movement of the lever 12 presses inwardly the valve stem 16 which connects a source of air supply to suitable cylinders, not shown, for moving the pusher, formed by the bars 10 and 11, inward to push the vessels into the leer. As the pusher 10 moves inwardly, the tripping device 17 attached to the transferring mechanism necessarily moves with it, as shown in Figure 2. The result is that the back of the member 32 slides on the lever 12, while the vessel 35 rests against the tripping device. This forward vessel is, therefore, securely supported on two sides and prevented from toppling over, as would frequently be the case if the vessel had to slide against the member engaging its side. In other words, the sliding movement is between the member 32 and the lever 12, both of which are pivoted in position as to the movement in the direction of the conveyor belt 6 and secured against any derangement. When the vessels have reached their proper position within the leer, the transferring mechanism is moved directly upward which does not affect the containers, since ordinarily they are conical or cylindrical, though not necessarily of this shape. Afterwards, the pusher is moved rearwardly over the incoming vessels on the belt 6 and downwardly to its original position ready for a second cycle of movement. If by any chance, the foremost vessel 35 should reach the end of its travel or should reach the position where it would ordinarily engage the tripping device before the tripping device is in proper position to be engaged, the vessel merely continues along the conveyor belt 6 and falls on the floor. However, were the vessel engaging means attached directly to the lever 12, the vessel would operate this lever irrespective of whether or not the pusher members 10 were in position to move forward. As a result, the lever 12 might be tripped repeat-

edly before the transferring mechanism reached its original position. Such a contingency would necessitate the attention of an operator to get the device back to its operating condition and to adjust the rate of movement of the conveyor 6.

It will be seen that the tripping device provided herein is simple in construction and may be readily applied to existing leer loaders. It is attached directly to the transferring mechanism; and in addition to tripping the mechanism for actuating the transferring device, it moves with and supports the vessels moved into the leer. There is no relative movement between the vessels and the tripping device during the movement into the leer. The tripping device, being attached to the transferring mechanism, is in position to be tripped only when the transferring mechanism is in position to commence its cycle of operation; hence the vessels cannot operate the trip unless the conveyor mechanism is in proper position. The entire mechanism is inclosed in a suitable box-like structure and is operated by vertical members extending outside of the closed end of the leer to avoid waste of heat and draughts of air which might affect the annealing operation. Further, the device is rigid in construction and fully capable of withstanding the rough usage to which it may be subjected.

As various changes may be made in the form, construction and arrangement of the parts of the preferred embodiment described above without departing from the spirit of the invention, it is to be understood that all matter herein set forth is to be interpreted as illustrative and not in a limited sense.

Having thus described my invention, I claim:

1. In a trip mechanism, the combination of a transferring device for moving a row of vessels from a conveyor, a valve adapted to effect the operation of said device, a lever for operating said valve, a bracket secured to said vessel transferring device, and a pivoted member adapted to oscillate laterally with respect to the movement of the transferring device, said pivoted member comprising an extending portion at the lower end thereof adapted to be engaged by one of the vessels moving along the conveyor, and a second extending portion above said first portion adapted to engage said lever, whereby the transferring device is operated to move the vessels from the conveyor.

2. In a device of the class described, the combination of a conveyor adapted to transfer vessels, a pusher extending along said conveyor for moving the vessels transversely thereof, a lever adapted to actuate means for operating said pusher, and an L-shaped member attached by one side to the further end of the pusher, the other side being normally in the path of the vessels moving on the con-

veyor, said side extending across the conveyor having a pivoted member suspended therefrom adapted to be oscillated by a vessel on the conveyor and, in turn, to actuate said lever for operating said pusher.

3. A tripping device comprising an L-shaped member, a downwardly extending arm pivoted to said member, and a stop portion for limiting the movement of said pivoted arm, a lateral extension on said arm adapted to permit the engagement of a moving vessel to oscillate said arm, and a second extension on said arm adapted to engage a lever adapted to operate a mechanism for transferring vessels from a conveyor.

4. In a device of the class described, the combination of a leer, a pusher for moving vessels into said leer, a depending lever pivotally mounted and adapted to oscillate freely with respect to said pusher for controlling the operation thereof and a second lever pivoted on said pusher at the side of said first lever for oscillating said first lever when the pusher is in ineffective position.

5. In a device of the class described, the combination of a conveyor for moving vessels, a member extending along said conveyor for pushing the vessels transversely thereof, and an elongated depending lever for controlling a mechanism adapted to operate said pushing member, and a suspended oscillating device attached to said member normally in the path of the vessels moving on the conveyor and at the side of said lever.

6. In a trip mechanism, the combination of a vessel transferring device, a trip lever pivoted substantially in alignment therewith when said device is in ineffective position, a supporting member attached to said vessel transferring device, a pivoted member suspended from said supporting member, portions on the back of said pivoted member adapted to engage said trip lever, and forwardly extending means on said pivoted member adapted to be engaged by moving vessels.

7. In a tripping device, the combination of a downwardly depending pivoted member adapted to be engaged and oscillated by a vessel moving along a conveyor to actuate means for operating a pusher, and a pusher adapted to move transversely to the plane in which said member is oscillated for transferring the vessel into a leer, said member being attached to the pusher and being adapted to move with the vessel as it is transferred into the leer, whereby said pusher cannot be operated until it has returned to its normal position.

8. In a tripping device, the combination of a conveyor for transferring a plurality of vessels, a pusher for moving the vessels transversely thereof, a supporting member attached to said pusher, an oscillating arm pivoted at its upper end and suspended from

said member adapted to be actuated by one of the vessels, portions on said arm for counterbalancing oscillation thereof, and stop portions on said supporting member for limiting the oscillation of said arm after a vessel has moved into engagement therewith.

9. In a device of the class described, the combination of a conveyor for presenting a row of vessels, a pusher for moving said vessels transversely thereof, a pivoted arm member suspended from said pusher in the path of the vessels moving on the conveyor, an extension on said arm member adapted to facilitate the engagement and oscillation thereof by one of the vessels, a valve for controlling the operation of said pusher, a lever pivoted intermediate said valve and arm member, said arm member being adapted to oscillate said lever and thereby operate said valve, whereby the pusher moves the row of vessels from the conveyor.
